UNITED STATES PATENT OFFICE

WALTER F. HELMKAMP, OF EAST MOLINE, ILLINOIS, ASSIGNOR TO DEERE & COMPANY,
OF MOLINE, ILLINOIS, A CORPORATION OF ILLINOIS

HARVESTER

Application filed June 3, 1929. Serial No. 368,017.

This invention relates to improvements in harvester.

The sickle of a modern harvesting machine is supported on a frame work on which it is driven back and forth, or oscillated, by the mechanism of the harvester. The framework also carries a plurality of fingers or sickle guards which project forward from the framework and guide the standing grain 10 into proper relation with the sickle to permit the sickle to sever it.

These fingers are usually constructed of cast iron and are held on the sickle framework by bolting or riveting. The upper face 15 of the finger is flat, and the cutting knives of the sickle are disposed immediately above this face in rubbing contact with it. Hence the edges of the upper face of the finger cooperate with the cutting blades of the sickle to 20 sever the grain by a shearing action, it is the customary practice to provide a ledger plate on this face, that plate usually being hardened to increase its life and effectiveness as a cutting shear.

These ledger plates must be made removable so that the cutting edges of them can be trued when necessary. To facilitate ready removal of these plates a recess is cast in the forward tip of the finger and a coil spring 30 set in this recess. The front edge of the ledger plate is designed to fit in this recess against the coil spring, and the back edge is beveled to fit in a beveled recess cast in the finger adjacent to the frame section of it.

To insert the ledger plates into the fingers they are positioned with the forward section against the coil spring, are pushed forward until the rear end of the plate is moved ahead of the recess in which it is to fit, and then 40 moved backward into that recess, the tension of the spring serving to hold the plate in place.

In the harvesters constructed heretofore, the rear edges of the ledger plates have been 45 straight lines, usually the plate being some-

what diamond shaped and designed to bear against a V-shaped recess in the back portion of the guard finger.

An arrangement of this kind is satisfactory if the tension in the coil spring is directed 50 along the central axis of the ledger plate, in which case the plate bears firmly against the two straight sides of the V socket in which it fits.

However, in the manufacture of these fingers it frequently happens that the core used to cast the spring socket in the finger becomes slightly displaced so that the socket is not properly aligned along the central axis of the finger. The result of this arrangement 55 is that when the spring is in place it exerts a tension on the ledger plate along the line that does not coincide with the center line of the plate and the tension is therefore unevenly distributed on the V-shaped socket at the rear 60 of the guard finger.

A ledger plate so held in the guard finger is very apt to be jarred loose or knocked out by the grain pushed against it by the sickle cutting member, with the consequent frequent 70 losing of the ledger plates and the bother of frequently replacing them.

In cases of extreme misalignment of the spring socket relative to the central axis of the finger, it may happen that the ledger 75 plate bears against the V socket only at the extreme tip point of the bearing surface, in which case the ledger plate is very insecurely held on the finger and it is most certain that it will be hammered loose by the grain beating against its cutting surface.

In my present invention I have provided a new ledger plate and redesigned finger guard in which the rearward edge of the ledger plate is formed as the arc of a circle. 85 The socket into which this plate fits is also formed as an arc of a circle of the same radius and the center points of the two circles coincide when the ledger plate is in its correct position.

By this arrangement, any misalignment of the coil spring that holds the ledger plate in the finger will not result in the ledger plate bearing against its rear socket only at a point, but rather the bearing will be distributed over the entire surface of the arcuate end of the plate and the socket into which it fits. I have provided a bevel on the rear end of the ledger plate and a corresponding undercut or bevel on the socket that is to receive it, so that the plate is firmly held on the guard finger and cannot be dislodged therefrom by the beating of the grain against the cutting edge of the ledger plate.

The firm lodging of the ledger plate on the guard finger may also be enhanced by forming the rear end of the ledger plate in a convex arc, and forming a concave or semi-circular indentation in the end of the plate, this indentation having its center located on the center line of the plate. The socket in the finger guard is made concave to register with the convex contour of the rear end of the ledger plate and is provided with a convex boss centrally located and designed to fit into the concave indentation in the ledger plate. Both the socket and the boss are undercut to receive the bevel edges of the ledger plate which is securely held on the guard finger by them.

To acquaint those skilled in the art with the teachings of my invention I have shown a preferred embodiment of it in the accompanying drawing in which;

Figure 1 is an elevation view of the guard finger;

Figure 2 is a cross sectional view taken along the line 2—2 of Figure 1;

Figure 3 is a section of the figure taken along the line 3—3 of Figure 1, looking in the direction of the arrows;

Figure 4 is a plan view of a modified form of finger; and

Figure 5 is a cross-sectional view of Figure 4 taken along the line 5—5 looking in the direction of the arrows.

As will be seen in Figures 1, 2 and 3 the guard finger is generally a spear shaped member that is usually formed of cast iron. At the rear end of the finger and on its upper face, a flat portion 20 and shoulder 21 are provided to facilitate attaching the finger to the sickle frame work, where it is held by a bolt or rivet extending through the hole 23.

A recess 22 in the shoulder 21 cooperates with a projection on the frame work to lock the finger thereon.

The leading end of the finger is tapered in all four directions to facilitate it nosing its way into the grain. The bottom face 7 is arcuate and slides along on the ground serving as a support for the sickle bar.

The sickle, not shown, rests in the depression 24 in the upper face of the finger and bears against the shoulder of the cutter bar

to which the guard fingers are bolted and which serves as a guide for the sickle. The cutting knives of the sickle project over the ledger plate 6 and beneath the upper guard 25, resting immediately adjacent the plate 6. 70

Since the cutting blades of the sickle push the grain over against the edge of the ledger plate 6, where it is cut by a shearing action between the cutting blade and the ledger plate edge, it is customary to make the ledger plates removable and to harden them. To facilitate this operation, a socket 12 is cast in the forward section of the finger, that socket being cylindrically shaped and centrally located in the finger. A coil spring 80 11 is fitted into the socket to facilitate holding the ledger plate in the finger, as will presently appear.

The guard finger is also provided with the curved surfaces 8, which are undercut slightly, thereby forming a socket. The center of the circle of which these curved surfaces are a part lies on the central axis of the finger.

The ledger plate 6 is formed with a projection 13', whose sides 13 snugly fit into the socket 12 in the forward part of the finger. The V point of this projection 13' fits into and engages the coil spring 11.

The rear end of the ledger plate 6 is formed as an arc of a circle, and is beveled with the wider edge of the bevel disposed at the bottom of the plate.

To insert the ledger plate 6 in the finger the projection 13' is brought into registration with the socket 12 and the V point of that projection into engagement with the spring 11. The rear end of the ledger plate is disposed over the shoulder 26 and to bring the curved surface 9 of the ledger plate into engagement with the socket 8 of the finger 100 the entire plate is pushed forward against the tension of the spring 11. After the plate has been pushed sufficiently far forward that its edges 9 are past the edges 8 of the socket, the plate is pushed downward into the plane 110 of the socket and the tension of spring 11 allowed to push it into the socket. The bevel edges 9 of the plate 6 cooperate with the bevel edge of the socket 8 to hold the plate down on the finger. 115

Since the bearing surface of the ledger plate 6 against the socket 8 is arcuate the plate will bear over the entire surface of the socket even though the center line of the spring 11 be slightly offset from the center line of the finger. This insures that the ledger plate will be securely held on the finger at all times even though the finger be imperfect by reason of having the socket 12 eccentrically disposed with respect to the center line of the finger instead of concentrically as it should be.

To facilitate removing the ledger plate 6 from the guard finger, I have provided a slotted opening 14 in the rear end of the plate. 130

It is customary to hollow out the guard finger beneath the ledger plate, as shown at 27, and the rear end 15 of this depression forms a ledge against which a lever projected through the opening 14 can rest. The ledge 15 forms a fulcrum to assist the lever in moving the ledger plate 6 forward to bring the beveled edges 9 of the plate out of engagement with the socket edges 8. After the plate has been thus moved back, it can be lifted up and removed in the obvious manner.

In Figures 4 and 5, I have shown a modified form of the invention in which I have provided a centrally located boss 9', against which the rear end of the ledger plate fits. This boss is preferably semicircular, with its center located at 10', which is on the center line of the guard finger. The edge 9 of the boss 9' is undercut and the edge 8' of the ledger plate 6, which cooperates with the boss, is beveled to fit in this undercut.

In this modification, the ledger plate 6 is held in the guard finger by the curved edge 8', which fits into a beveled socket to hold the plate firmly down on the guard. The plate is inserted in the guard in the above explained manner and to facilitate moving it, I have provided the hole 14, through which a nail or other similar rod may be brought to bear against the edge 15' of the depression 27 which acts as a fulcrum to spring the ledger plate 6 forward out of engagement with the socket.

From the foregoing it will be seen that the curved rear edge of the ledger plate and its cooperating curved sockets permit solid seating of the plate in the socket even though the tension put on the plate by the spring 11 be along a line which does not coincide exactly with the center line of the guard finger and plate. The danger of the ledger plate being knocked out of its socket by the grain pushed against it by the sickle bar is removed, and although the ledger plate is firmly locked against such accidental displacement it is readily removable by the use of simple tools when it is necessary to repair or replace it.

The use of a round end ledger plate 6 permits the use of many guard finger castings which would have to be discarded because of a misalignment of the socket 12 if the straight edged guard plate, used heretofore, were employed. The core which forms the socket 12 is apt to be slightly displaced in the casting process so that the socket is not perfectly aligned as it should be. This misalignment is not great and I have found that the use of the circular socket and circular end of the ledger plate permits proper seating of the plate in these fingers even when the socket 12 is misaligned.

It will be noted that when the ledger plate is in place on the guard finger, its upper face fits flush with the upper face of the shoulder 26, and also flush with the upper face of boss

9'. In other words, the face of the finger over which the blades of the sickle run is smooth and flat so that the blades may be located very close to or actually touching the guard finger and ledger plate mounted thereon. The 70 blades thus operated form one blade of a shear, with the ledger plate edge forming the other blade, with the result that the grain is cleanly cut and the sickle therefore not choked or fouled. 75

While I have chosen to show a preferred embodiment of my invention I have done so by way of example only as there are many modifications and adaptations which can be made by one skilled in the art without departing from the teachings of the invention. 80

Having thus complied with the statutes and shown and described a preferred embodiment of my invention, what I consider new and desire to have protected by Letters Patent is 85 pointed out in the appended claims.

What is claimed is:

1. In a guard finger for harvesters, arcuate shoulder means, a ledger plate having a round end conforming to the arc of said shoulder means, a socket disposed in said finger opposite said shoulder means, a tongue on said plate registering with said socket, and means in said socket for holding the round end of said plate firmly against said arcuate shoulder means. 90

2. A guard finger for harvesters, comprising a casting, a flat face on said casting, arcuate shoulder means rising from said face, said shoulder means having a sloping edge the 100 top of which overhangs said plane to form a cavity, a socket formed in said casting, a ledger plate having a beveled, rounded end registering with said shoulder means and cavity, a tongue on said plate registering 105 with said socket, and means in said socket for holding the rounded end of said plate securely against said shoulder means and in said cavity to thereby hold the plate on said casting. 110

3. A guard finger for harvesters, comprising a casting, a flat face on said casting, arcuate shoulder means rising from said face, a ledger plate having a rounded end registering with said shoulder means, a socket formed in said casting, a tongue on said plate registering 115 with said socket, and a coil spring in said socket for holding the round end of said plate securely against said shoulder means to thereby hold the plate on said casting. 120

4. In a guard finger for harvesters, arcuate shoulder means having a beveled edge forming a recess, the center of said shoulder means being disposed on the center line of said finger, a cylindrical socket in said finger 125 disposed with its axis substantially on the center line of said finger, a ledger plate shaped to conform to the contour of said finger, a beveled arcuate end on said plate registering with said shoulder means, a 130

tongue on said plate registering with said socket, and means in said socket for holding said plate on said finger.

5. In a guard finger for harvesters, an arcuate shoulder having a beveled edge, the center of said shoulder being disposed on the center line of said finger, a cylindrical socket in said finger disposed with its axis substantially on the center line of said finger, a ledger plate shaped to conform to the contour of said finger, a beveled arcuate end on said plate registering with said shoulder, a tongue on said plate registering with said socket, and means in said socket bearing 10 against said plate along its center line to hold its arcuate end against said arcuate shoulder.

6. In a guard finger for harvesters, an arcuate shoulder, a ledger plate having an opening therein, a beveled and rounded end on said plate, a socket disposed in said finger opposite said shoulders, a flat face on said finger between said socket and shoulder, a tongue on said plate registering with said 25 socket when said plate is disposed on said flat face with said round end registering with said shoulder, means in said socket bearing against said tongue to hold said plate in place on said finger, and a recess in said flat 30 face, the edge of which serves as a fulcrum for a lever projected through the opening in said plate to remove it from said finger.

7. In a sickle bar finger for harvesters, an arcuate shoulder on said finger, a semicircular undercut boss projecting centrally from said finger, a ledger plate having an arcuate end with a semicircular slot disposed in the center of the end, a socket disposed in said finger opposite said shoulder, a tongue on 40 said plate registering therewith, and means in said socket for positively maintaining the plate in position on said finger with its slot properly seated relative to the undercut boss.

8. In a guard finger for harvesters, comprising a casting having a flat shoulder surface for attaching the finger to a sickle frame, a tapered finger-like portion disposed with its center line at right angles to said shouldered surface, a flat face disposed on said finger, a 45 recess in said face, an undercut shoulder adjacent to said face, said shoulder being formed as the arc of a circle whose center lies on the center line of said finger, a socket opposing said shoulder and concentric with said center 50 line, a ledger plate for said finger, said plate having a beveled rounded end registering with said undercut shoulder, a slot in that end and a tongue on the other end registering with said socket, and a coil spring disposed 55 in said socket and bearing against said tongue to hold the ledger plate on said finger by holding the rounded end thereof firmly against said undercut shoulder, the edge of said recess forming a fulcrum for a pointed rod 60 projected through the slot in said plate to

move it against the tension of said spring to remove it from said finger.

9. The combination with a guard finger for harvesters, said guard finger having an arcuate shoulder, of a ledger plate having one end arcuate in shape, and means for releasably holding said ledger plate on said guard finger with its arcuate shaped end in positive engagement with said shoulder.

10. The combination with a guard finger 75 for harvesters, said guard finger having an arcuate recess, of a ledger plate having one end shaped to register with said recess and means for yieldingly holding said ledger plate on said finger with its shaped end in engagement with said recess.

11. The combination with a guard finger for harvesters, said guard finger having an arcuate recess, of a ledger plate having one end shaped to register with said recess and 85 means carried by said finger for yieldingly holding said ledger plate on said finger with its shaped end in engagement with said recess.

12. The combination with a guard finger 90 for harvesters, said guard finger having an undercut arcuate recess, of a ledger plate having one end shaped to seat in said recess, and means for yieldingly holding said ledger plate on said finger with the shaped end there- 95 of seated in said recess.

13. A guard finger for harvesters comprising a casting with a flat face thereon, oppositely projecting shoulders having concave undercut surfaces, said casting having a socket disposed substantially centrally therein, a ledger plate having a convex tapered end registering under said undercut shoulders, and means in said socket for maintaining said ledger plate on the casting with its convex 105 surface in full engagement with said concave undercut surface.

14. A guard finger for a harvester comprising a casting with a shoulder formed thereon, said casting having a socket disposed in the 110 casting substantially centrally thereof, a ledger plate carried by said casting, said shoulder having a groove for the reception of said ledger plate and means in said socket for maintaining the ledger plate against said 115 shoulder, the ledger plate being capable of conforming with said shoulder and socket means to be held on the casting.

15. A self-adjusting ledger plate in combination with a harvester guard finger, said 120 guard finger having a flat supporting surface and an arcuate abutting surface associated with said supporting surface, said arcuate abutting surface lying in the arc of a circle 125 the axis of which is located in the longitudinal center of said finger, socket means opposing said arcuate abutting surface and adapted to yielding contact with said ledger plate, said ledger plate having an arcuate end conforming to and engaging with said arcuate 130

abutting surface whereby said ledger plate is adapted to turn on the supporting surface so that its arcuate end will be in full engagement with the arcuate abutting surface on said

5 guard finger.

In witness whereof, I hereunto subscribe my name this 24th day of May, 1929.
